UNITED STATES PATENT OFFICE.

WILLIAM F. HUFF, OF LONG BEACH, CALIFORNIA, ASSIGNOR OF THREE THIRTY-SECONDS TO E. C. NEWBURY, THREE THIRTY-SECONDS TO C. E. NEWBURY, THREE-SIXTEENTHS TO T. J. DEEBLE, THREE-SIXTEENTHS TO C. L. CRANDALL, AND THREE-SIXTEENTHS TO F. C. WILSON, ALL OF LONG BEACH, CALIFORNIA.

SANITARY BOTTLE-CLOSURE.

1,111,259.

Specification of Letters Patent.

Patented Sept. 22, 1914.

Application filed October 22, 1913. Serial No. 796,735.

To all whom it may concern:

Be it known that I, WILLIAM F. HUFF, a citizen of the United States, residing at Long Beach, in the county of Los Angeles 5 and State of California, have invented a new and useful Sanitary Bottle-Closure, of which the following is a specification.

My invention relates to improvements in sanitary bottle closures, and the object of my 10 invention is to provide a sanitary covering or closure for milk bottles or the like to prevent the accumulation of dust and germs on the mouth of the bottle which may be frictionally held in and easily removed from position in the bottle.

Other objects may appear in the subjoined description.

I attain this object by means of the mechanism illustrated in the accompanying drawings, in which—

Figure 1 is an elevation of a bottle showing the top thereof in section and with my closure in position at the top. Fig. 2 is a bottom view of a pasteboard blank disk before it is formed as shown in Fig. 1. Fig. 3 is a section through the center of Fig. 2.

Similar reference numerals refer to the same parts throughout the several views of the drawings.

My closure is adapted principally for use 30 in connection with the common type of milk bottles, in which an annular shoulder 5 is provided on the inner side of the neck of the bottles for the purpose of seating a closure 35 or cap against, and that portion of the inner side of the neck immediately above this shoulder tapers or inclines inwardly therefrom in order to hold the closure in place after it has been forced into position against 40 the shoulder. I am aware of patents having been granted to Ray and Russel Patent #1,038,651 in which a closure is provided which partakes somewhat of the form of my invention, but in which the locking feature 45 of my invention as herein disclosed is not included, and over which said locking fea-

ture is a distinct improvement. Reference is also had to a previous application filed by me Aug. 14, 1913, Serial #784,764, in which other valuable improvements are disclosed. 50

My closure is first formed into a circular disk as shown in Fig. 2 after which by a suitable means a circular cut 7 is made in one side of the disk, said cut being concentric with regard to the periphery of the disk. 55 The disk may then be placed in a forming die and formed into the shape as shown in Fig. 1. The cut 7 is designed to extend not quite through the thickness of the disk, and when formed as in Fig. 1, the exterior portion 60 of the disk 3 is curved outwardly and downwardly so as to rest upon and completely cover the top edge 8 of the neck of the bottle 2, the outer side of the cut 7 will rest upon the annular shoulder 5 in the neck of the 65 bottle and the inner edge of the cut will occupy the space in the center of the bottle adjacent to said shoulder and the central portion of the closure 6 serves to cover the opening in the neck. The inner and lower 70 portion of the part 3 will engage the inclined portion of the neck and serve to retain the closure in the bottle. In this manner, the top edge of the bottle may be prevented from accumulating dust and germs, and the closure rendered easily removable from the bottle, the latter operation being accomplished by grasping the edge of the curved portion 75 3 and pulling it upwardly from its seat in the neck. 80

What I claim as my invention and desire Letters Patent for is:

1. The combination of a bottle having an annular shoulder formed in the neck thereof; and a closure disk having an annular groove cut in one side, the outer edge of said groove being adapted to rest upon said shoulder and the inner edge thereof to engage the side of said shoulder for holding said disk firmly in position in said bottle. 85

2. The combination of a bottle having an annular shoulder formed in the neck there-

of; and a closure disk having an annular groove cut in one side, the outer edge of which is adapted to rest upon the top and the inner edge to engage the side of said shoulder; the inner portion of said disk within said groove forming a closure for the neck and the outer portion thereof being

bent outwardly and upwardly around the edge of said neck.

WILLIAM F. HUFF.
